Inventor

Adam Lantz

UNITED STATES PATENT OFFICE.

ADAM LAUTZ, OF EAST ST. LOUIS, ILLINOIS.

AUTOMATIC OIL CUP FOR AIR PUMPS.

1,402,939.

Specification of Letters Patent. Patented Jan. 10, 1922.

Application filed February 16, 1921. Serial No. 445,304.

To all whom it may concern:

Be it known that I, ADAM LAUTZ, a citizen of the United States, and resident of East St. Louis, Illinois, have invented certain new and useful Improvements in an Automatic Oil Cup for Air Pumps, of which the following is a specification.

This invention relates to improvements in an automatic oil cup for air pumps, and has for its object a suitable casing in which is provided an oil receptacle and a vertical oil passage through which the oil is raised by means of air pressure in the top of the receptacle and from this passage the oil is fed in a small quantity through a downward port and communicating with a ball valve which likewise operates under air pressure, and by this manipulation a small quantity of oil is fed from the oil receptacle down through a port in the base of the casing and enters into the cylinder of the air pump.

The operation is controlled by the reciprocatory action of the piston in the cylinder of the air pump, that is by the movement of the piston while compressing the air therein has a tendency to close the ball valve yet permitting a small supply of air to pass into the receptacle and during the back stroke of the piston the ball is released and a small particle of the oil is permitted to pass through the port and flow into the cylinder.

Figure 1, is a vertical sectional view of my complete invention.

35. Fig. 2, is a top plan view of the same.

Fig. 3, is a horizontal sectional view taken on the line 3—3 of Fig. 1.

Fig. 4, is a sectional view taken on the line 4—4 of Fig. 1.

40. Fig. 5, is a sectional view taken on the line 5—5 of Fig. 1.

Fig. 6, is a sectional view taken on the line 6—6 of Fig. 1.

In the general construction of my invention I provide a suitable casing 7 in which is located an oil receptacle 8, the base 9 of the casing terminates into a screw-threaded projection 10 by which the casing is attached to the cylinder of the pump.

50. From the base portion of the casing and

extending upwardly through the receptacle is a hollow arm 11 which extends into a dome 12 formed in the top of the casing, the upper end of said arm is located a short distance from the top of the dome and in 55 said arm is a small outlet or port 13 which extends into the interior or large vertical port 14 formed in the arm, and extending through the base. In the top of the arm and at a suitable distance beneath the port 60 13 is placed a cross pin 15 which supports a ball valve 16, the tendency of which is to close the port 13 when air pressure is directed into the port 14.

To one side of the casing is formed a projection 17, and in the same is formed a vertical port 18 which communicates at its bottom with the lower portion of the receptacle 8, the upper end of the port 18 terminates into a horizontal port 19, this port 70 communicates with a vertical bore or passage 20 which extends through the entire projection 17 and in the upper portion of the bore is inserted a stem 21, the top being provided with a head 22 terminating into 75 screw threaded portion 23 by which the stem is held in position in the top of the bore. In this stem is provided a vertical port 24 and this port has communication with the horizontal port 19 by means of 80 radial ports 25 formed in the stem.

The bottom of the stem has a portion of itself reduced in diameter as that indicated by the numeral 26, the bottom edge being slightly counter-sunk so as to act as a seat 85 for the ball 27, and in the reduced portion above the counter-sunk seat are radial ports 28 which communicate with the vertical port 24.

In the bottom of the vertical bore 20 is inserted an adjusting stem 29, its upper portion is provided with screw-threads 30 which operate in screw threads 31 formed in the lower portion of the bore 20, a portion of this adjusting stem is provided with a vertical port 32 and terminates into radial ports 33, a portion of this adjusting stem is reduced in diameter as that shown at 34.

In the base of the casing and in alignment with the radial ports 33 of the stem 29 is 100

a horizontal port or oil passage 35, this passage communicates with the vertical passage 14 through which a small portion of oil after having passed through the bore 20 5 and its ports flows into the cylinder of the air pump.

Leakage around the adjusting stem 29 is prevented by means of the packing nut 36.

On the upper portion and to one side of 10 the casing is provided an extension 37 in which a plug 38 is inserted and through this projection when the plug is removed, oil may be inserted into the receptacle and acts as a filling medium. This plug is provided with an air escape vent 39 which permits the air to gradually escape when unloosening the plug so as to prevent the oil from being forced out through the opening under the air pressure which is in the upper portion of the receptacle and above the oil line. It likewise acts as an indicator 15 to test the working of the cup while the pump is in action.

The top of the casing as well as the plug 25 are provided with heads 40 to which a chain 41 or like device is attached so as to prevent the plug when removed from its position from becoming lost or mis-placed.

The operation of my invention is as follows:

When the device has been placed in position on the cylinder of an air pump and the receptacle filled with oil, the adjusting stem 29 is then manipulated to properly adjust 30 the movement of the ball valve carried thereby, when the same has been properly adjusted its action is as follows:

By the reciprocatory movement of the piston in the air pump the air pressure will 40 enter into the port 14, a portion of the air passing upward raising the ball 16 in the top of the arm, closing the port 13, some of the air also passes through the horizontal port 35, and through the radial ports 33 45 communicating with the ball 27, forcing it upward into the valve seat formed in the bottom of the reduced portion 26 of the stem 21, this closes off the direct communication 50 of the air with the vertical port 24 formed in the stem 21, but on account of the reduced portion permits a small amount of air to pass around and enter into the radial ports 28. This air passes upwardly and through 55 the port 24 and into the horizontal port 19 and then percolating downwardly through the oil in the vertical port 18 and then permits the same to pass upwardly through the body of oil in the receptacle and lodge in the dome. The air pressure in the dome after 60 the continuous operation of the pump assumes a pressure of approximately ninety pounds.

During the reverse action of the piston the air pressure in the dome acts upon the body 65 of oil and has a tendency to force the oil

from the receptacle up through the port 18 through the radial ports 25 down through the port 24 and lodge around the ball 27, this oil is prevented from escaping on account of the ball closing the port 32 located 70 in the adjusting stem 29.

When the pump piston is working in compression action and the ball 27 again raised, this particle of oil above and around the ball will pass around and enter into the port 32, 75 then during the reverse action of the piston, this oil is drawn from the port 32 through the radial ports 33 into the ports 35 and 14 to the cylinder. The ball 16 in the top of the arm has a tendency to check the passage 80 of air from the port to the dome, but to relieve some of the pressure from the dome during the reverse movement of the piston. By this construction of oil cup the oil is fed from the cup first upwardly then downwardly through the several passages and 85 permitted to enter the cylinder drop by drop, or in such small portion as may be required for proper lubrication and the quantity of oil is governed by the adjustment of the adjusting stem 29.

The circulation of air in the cup has a tendency to heat or warm the oil in the receptacle.

When it becomes necessary to fill the cup 95 with oil the operator can tighten down the adjusting plug so that the ball 27 is held firm between the valve seats. This will cut off both oil and air circulation.

Having fully described my invention what I claim is:

1. An automatic oil cup comprising a casing, a receptacle formed therein, a hollow arm formed integral with the base and extending to approximately the top of the receptacle, an extension formed on the casing in which is provided a port and a bore, a valve mechanism located in the bore and a passage communicating the bore with the port formed in the casing through which oil in small quantity may be passed from the receptacle into the cylinder of the pump, substantially as specified.

2. A device of the character described comprising a cup having an oil receptacle, a port formed in one side thereof, through which oil from the cup is passed upwardly, a bore formed in the projection, said bore being in communication with the vertical port, a stem inserted in the bore and provided with an oil passage, an adjusting stem located in the lower portion of the bore, a ball valve carried by the adjusting stem for regulating the passage of the oil, a hollow projection projecting from the base to approximately the top of the oil receptacle and a ball valve located in the top of the hollow projection, substantially as specified.

3. An automatic oil cup comprising a casing having an oil receptacle, an oil passage 130

communicating with the receptacle near the bottom thereof for permitting the oil to pass upwardly from the receptacle and then downwardly through a separate passage, a mechanism carried by the casing through which the oil from the vertical passage is directed downwardly, a valve located in the mechanism for regulating the flow of the oil and the passage of the air and a means for regulating the quantity of

the oil to be delivered to the cylinder, substantially as specified.

In testimony whereof, I have signed my name to this specification, in presence of two subscribing witnesses.

ADAM LAUTZ.
